[57] **CLAIM**

The ornamental design for combined integrated circuit package carrier and socket, as shown and described.

DESCRIPTION

FIG. 1 is a top plan view of combined integrated circuit package carrier and socket, showing our new design.

FIG. 2 is a left side elevational view thereof.

FIG. 3 is a bottom plan view thereof.

FIG. 4 is a right side elevational view thereof.

FIG. 5 is a front elevational view thereof.

FIG. 6 is a rear elevational view thereof.

FIG. 7 is an isometric view thereof looking generally downward.

FIG. 8 is an isometric view thereof on a reduced scale looking generally upward.
